CLAIM

The ornamental design for a mobile service cart as shown and described.

DESCRIPTION

FIG. 1 is a front, left, and top perspective view of the mobile service cart of the present invention.

FIG. 2 is a front elevation view thereof.

FIG. 3 is a back elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken lines in the drawings illustrate portions of the mobile service cart that form no part of the claimed design.

1 Claim, 6 Drawing Sheets
